PAUL J. SIMMEN, OF EDEN, NEW YORK

AUTOMATIC TRAIN CONTROL

Application filed February 10, 1928, Serial No. 618,193. Renewed May 17, 1928.

This invention relates to railway signalling systems, especially to systems in which instrumentalities for the control of a train are positioned both along the trackway and on the train, and more particularly to systems in which the instrumentalities are controlled both manually and by the presence or absence of a train upon the trackway.

In describing the invention in detail reference is had to the accompanying drawings wherein I have illustrated a preferred physical embodiment of my invention and wherein like characters of reference designate corresponding parts throughout the several

views and in which:

Figure 1 is a diagrammatic representation of the apparatus and circuits in a dispatcher's office and along a track; Fig. 2, illustrates the apparatus and circuits on a locomotive or car by which, with certain cooperating parts of Fig. 1, the signals are repeated on the locomotive or car.

In Fig. 1 are shown six signals for each block, designated as Nos. 1, 2, 3, 4, 5 and 6. These signals are erected along the trackway at suitable locations in the usual manner, so as to be easily visible to an engineer on an approaching train. These six signals are controlled by the several positions of a polarized relay 10 and an alternating current relay 11 both of which are along the trackway suitably housed. In the dispatcher's office are corresponding relays, a polarized relay 12, and an alternating current relay 13. The several positions of the armatures of relays 12 and 13, control six perforating magnets 14, 15, 16, 17, 18 and 19. These perforating magnets are located adjacent to a record sheet 20 in the dispatcher's office, so that when the perforating magnets are operated, perforating needles 21, will make a perforation on the record sheet. When signal No. 1 is displayed along the track perforating magnet 14 will operate; when signal No. 2 is displayed along the track perforating magnet 15 will operate; when signal No. 3 is displayed along the track, perforating magnet 16 will operate; when signal No. 4 is displayed along the track, perforating magnet 17 will operate; when signal No. 5 is displayed along the

track, perforating magnet 18 will operate; and when signal No. 6 is displayed along the track, perforating magnet 19 will operate.

Fig. 1 shows a track consisting of rails 1 and 2. Rail 1 is electrically continuous and rail 2 is divided into sections by means of insulating joints 3, thus dividing the track into block sections. Near one end of each block is a track battery 4 and near the other end of the block is a track relay 5, constituting with their connections to the rails, a track circuit well known in the art. Each track relay controls an armature 6, which when the track relay is energized, closes three front contacts 7, 8 and 9, and when the track relay is deenergized, the armature drops and opens these front contacts. Front contact 7 is connected by wire 22 to impedance coil 23 and thence by wire 24 to polarized relay 10 and thence by wire 25 and wire 26 to track rail 1. Front contact 8 is connected by wire 27 to condenser 28 and thence by wire 29 to alternating current relay 11 and thence by wire 30 and 26 to track rail 1. Front contact 9 is connected by wire 31 to train control rails 32 and 33, the operation of which will be described hereinafter. From the hinged end 34 of armature 6 of track relay 5, a line wire 35 connects to a terminal 36 at the dispatcher's office. From this terminal 36 extend three distinct branches, these being parts of circuits which are established by means of manually operable switches 37 and 38 through positive battery 39, negative battery 40 and alternating current generator 41.

The first circuit is as follows:—from terminal 36, impedance coil 42, wire 43, polarized relay 12, switch 37, spring terminal 44, wire 45, bus 46, to positive pole of battery 39 and thence from negative pole of battery 39 through wire 47, wire 48 and wire 49 to a connection with track rail 1.

The second circuit is as follows:—from terminal 36, impedance coil 42, wire 43, polarized relay 12, switch 37, spring contact 50, wire 51, bus 52, to negative pole of battery 40 and thence by wires 53, 48 and 49 to a connection with track rail 1.

The third circuit is as follows:—from terminal 36, condenser 54, wire 55, alternating

current relay 13, manually operable switch 38, spring contact 56, wire 57, bus 58, condenser 205 to alternating current generator 41 and thence by wires 59 and 49 to a connection with track rail 1.

5 Impedance coils 42 are inserted to prevent the flow of alternating current through the circuit in which they are inserted, and condensers 54 and 205 to prevent the flow of direct current through the circuit, in which they are inserted.

10 By means of these three last described circuits, depending upon the positions of the manually operable switches 37 and 38, six different electrical conditions can be established in the relays 10 and 11 along the track and in the relays 12 and 13 in the dispatcher's 15 office as follows:

20 *First condition.*—When switch 37 is in contact with spring contact 44 and switch 38 is in contact with spring contact 56, polarized relays 10 and 12 are positively energized and alternating current relays 11 and 13 are also energized.

25 *Second condition.*—When switch 37 is in contact with spring contact 50 and switch 38 is in contact with spring contact 56, polarized relays 10 and 12 are negatively energized and alternating current relays 11 and 13 are 30 also energized.

35 *Third condition.*—When switch 37 is in contact with spring contact 44 and switch 38 is open, polarized relays 10 and 12 are positively energized but alternating current relays 11 and 13 are deenergized.

40 *Fourth condition.*—When switch 37 is in contact with spring contact 50 and switch 38 is open, polarized relays 10 and 12 are negatively energized, but alternating current relays 11 and 13 are deenergized.

45 *Fifth condition.*—When switch 37 is open and switch 38 makes contact with contact spring 56, the polarized relays 10 and 12 are deenergized, but alternating current relays 11 and 13 are now energized.

50 *Sixth condition.*—When switches 37 and 38 are both open, all four relays 10 and 12 and 11 and 13 are deenergized.

55 I will now describe the three circuits by which the polarized relays 10 and 12 are either positively energized or negatively energized with direct current and the circuit by which alternating current relays 11 and 13 are energized, the several combinations of which control signals Nos. 1, 2, 3, 4 and 5 and the corresponding perforating magnets 14, 15, 16, 17 and 18.

60 *Positive direct current circuit.*—From positive pole of battery 39 in the dispatcher's office, bus 46, wire 45, contact spring 44, switch 37, polarized relay 12, wire 43, impedance coil 42, terminal 36, line wire 35, armature 6 of track relay 5, front contact 7, wire 22, impedance coil 23, wire 24, polarized relay 10, wires 25 and 26 to track rail 1 and thence

through wires 49, 48 and 47 to the negative pole of battery 39.

65 *Negative direct current circuit.*—From negative side of battery 40 in the dispatcher's office, bus 52, wire 51, contact spring 50, 70 switch 37, polarized relay 12, wire 43, impedance coil 42, terminal 36, line wire 35, armature 6 of track relay 5, front contact 7, wire 22, impedance coil 23, wire 24, polarized relay 10, wires 25 and 26 to track rail 1 and 75 thence by wires 49, 48 and 53 to the positive side of battery 40, this circuit being traced against the flow of current.

80 *Alternating current circuit.*—Alternating current generator 41 in the dispatcher's office, 85 condenser 205, bus 58, wire 57, contact spring 56, switch 38, alternating current relay 13, wire 55, condenser 54, terminal 36, line wire 35, armature 6 of track relay 5, front contact 8, wire 27, condenser 28, wire 29, alternating 85 current relay 11, wires 30 and 26 to track rail 1 and thence by wires 49 and 59 to the alternating current generator 41.

90 Impedance coil 23 is inserted to prevent the flow of alternating current through the circuit in which it is inserted, and condenser 28 is inserted to prevent the flow of direct current through the circuit in which it is inserted.

95 I will now describe the operation of signals Nos. 1, 2, 3, 4, 5 and 6, depending upon the several electrical conditions of polarized relay 10 and alternating current relay 11.

100 When polarized relay 10 is energized with positive direct current and alternating current relay 11 is energized with alternating current, neutral armatures 60 and 61 of relay 10 make contact with front contacts 62 and 63; and polarized armatures 64 and 65 are in the right hand position and armatures 66 of relay 11 make contact with front contact 67. This position of the several armatures establishes a circuit through signal No. 1 as follows:—from battery 68, wire 69, armature 66, front contact 67, wire 70, armature 60, front contact 62, wire 71, armature 64, to contact 72, signal No. 1, wire 73 to other side of battery 68.

115 When polarized relay 10 is energized with negative direct current and alternating current relay 11 is energized with alternating current, neutral armatures 60 and 61 of relay 10 make contact with front contacts 62 and 63, but polarized armatures 64 and 65 are now in the left hand position and armature 66 of relay 11 makes contact with front contact 67. This position of the several armatures establishes a circuit through signal No. 2 as follows:—from battery 68, wire 69, armature 66, front contact 67, wire 70, armature 60, front contact 62, wire 71, polarized armature 64, contact 74, signal No. 2, and wire 73 to the other side of battery 68.

120 When polarized relay 10 is energized with positive direct current, and alternating cur-

rent relay 11 is deenergized, neutral armatures 60 and 61 of relay 10 make contact with front contacts 62 and 63 and polarized armatures 64 and 65 are in the right hand position. 5 Armature 66 of relay 11 makes contact with back contact 75. This position of the several armatures establishes a circuit through signal No. 3 as follows:—from battery 68, wire 69, armature 66, back contact 75, wire 76, 10 armature 61, front contact 63, wire 77, armature 65, contact 78, signal No. 3, wire 73 to other side of battery 68.

When polarized relay 10 is energized with negative direct current, and alternating current 15 relay 11 is de-energized, neutral armatures 60 and 61 of relay 10 make contact with front contacts 62 and 63 and polarized armatures 64 and 65 are in the left hand position. Armature 66, of relay 11 makes contact with 20 back contact 75. This position of the several armatures establishes a circuit through signal No. 4 as follows:—from battery 68, wire 69, armature 66, back contact 75, wire 76, armature 61, front contact 63, wire 77, polarized armature 65, contact 79, signal No. 4, and wire 73 to the other side of battery 63.

When polarized relay 10 is deenergized and alternating current relay 11 is energized with alternating current, neutral armatures 60 and 25 61 of relay 10 make contact with back contacts 80 and 81. Armature 66 of relay 11 makes contact with front contact 67. This position of the several armatures establishes a circuit through signal No. 5 as follows:— 30 from battery 68, wire 69, armature 66, front contact 67, wire 70, armature 60, back contact 80, wire 82, signal No. 5 and wire 73 to the other side of battery 68.

When polarized relay 10 is deenergized and 35 alternating current relay 11 is also deenergized neutral armatures 60 and 61 of relay 10 make contact with back contacts 80 and 81. Armature 66 of relay 11 makes contact with back contact 75. This position of the several armatures establishes a circuit through 40 signal No. 6 as follows:—from battery 68, wire 69, armature 66, back contact 75, wire 76, armature 61, back contact 81, wire 83, signal No. 6 and wire 73 to the other side of battery 45 68.

It will thus be seen that the dispatcher may 50 display any one of the six signals by the several positions of the manually operable switches 37 and 38, but in addition to this manual control by the dispatcher, automatic control of these signals is also provided for by a track circuit in the following manner:— 55 As long as there is no train in the block ahead, track relay 5 is energized, and armature 6 of track relay 5 closes front contacts 7, 8 and 9, thus permitting flow of current from the dispatcher's office, when however a train is in the block ahead, as shown in hatched lines, the energy from track battery 4 is short circuited 60 through the wheels and axles of the train 65

in the manner well known to one skilled in the art, and track relay 5 is therefore, not sufficiently energized to maintain armature 6 in the position to maintain contact with front contacts 7, 8 and 9 consequently armature 6 drops away and these front contacts are 70 broken, so that when this condition exists no electrical energy can reach relays 10 or 11, and these relays become deenergized, so that invariably signal No. 6 will be displayed 75 when there is a train in the block ahead, irrespective of whether switches 37 and 38 in the dispatcher's office are positioned to send electrical energy to relays 10 and 11.

Devices Nos. 1, 2, 3, 4, 5 and 6 are merely 80 schematic and may be signal lamps which are lighted when their respective circuits are closed, or they may be translating devices such as relays by which circuits are controlled to operate semaphore signals, or any other electrical device, in a manner well known to those skilled in the art.

I will now describe the recording apparatus 85 in the dispatcher's office. A record sheet 20 is suitably mounted and driven by a roller 84, which in turn is driven by a shaft 85. Shaft 85 receives motion through ratchet wheel 86. A pawl 87 is pivotally connected to armature 88 of electromagnet 89. Armature 88 is hinged at 90. When electro-magnet 89 is 90 periodically energized, motion is given to the ratchet wheel through pawl 87. A spring 91 normally pulls armature 88 and pawl 87 to the right, when electro-magnet 89 is not energized. Electro-magnet 89 is connected by 95 wire 93 to a make-and-break device 92, which make-and-break device is periodically operated by clock work 94, this may well be of the form shown in my prior patent No. 1,203,146 granted Oct. 21, 1916. When the make-and-break device is closed, the electro-magnet 89 is energized through the following circuit:— 100 battery 95, wire 96, magnet 89, wire 93, make-and-break device 92, wires 97 and 98, to the other side of battery 95. The make-and-break device 92 is operated, say every 5 seconds, by the clock work so as to give a slow and uniform movement to the record sheet 20, 105 through ratchet wheel 86 and pawl 87.

The record sheet 20 is transversely divided 110 into sections as 99, 100 and 101, each section representing a block along the track. Longitudinally the record sheet is divided into time lines such as 1 a. m., each one of the lines representing a one minute interval. Since the 115 make-and-break device 92 is operated continuously, it will be seen that longitudinally the record sheet assumes a constantly changing position, during the 24 hours of the day.

Adjacent to record sheet 20 are located 120 perforating magnets 14, 15, 16, 17, 18 and 19, for each space representing a block upon the record sheet. Pivotally attached to the armatures of these perforating magnets are perforating needles 21 so positioned adjacent to 125

the record sheet that when a perforating magnet is energized, a perforation is made upon the record sheet. There are six such perforating magnets for each block, so positioned that transversely each perforating magnet perforates in a different position. The circuits to these perforating magnets are closed in a manner very similar to the circuits closed through signals Nos. 1, 2, 3, 4, 5 and 6, and I will now proceed to describe the operation of these circuits.

When polarized relay 12 is energized with positive direct current and alternating current relay 13 is energized with alternating current, neutral armatures 102 and 103 of polarized relay 12 make contact with front contacts 104 and 105 and polarized armatures 106 and 107 are in the right hand position and armature 108 of relay 13 makes contact with front contact 109. This position of the several armatures establishes a circuit through perforating magnet 14 as follows:—from battery 95, wire 98, wire 110, armature 108, front contact 109, wire 111, armature 102, front contact 104, wire 112, polarized armature 106, contact 113, wire 114, perforating magnet 14, wire 115, bus 116, wire 117, to the other side of battery 95.

When polarized relay 12 is energized with negative direct current and alternating current relay 13 is energized with alternating current, neutral armatures 102 and 103 of relay 12 make contact with front contacts 104 and 105 and polarized armatures 106 and 107 of relay 12 are now in the left hand position. Armature 108 of relay 13 makes contact with front contact 109. This position of the several armatures establishes a circuit through perforating magnet 15 as follows:—from battery 95, wires 98 and 110, armature 108, front contact 109, wire 111, armature 102, front contact 104, wire 112, polarized armature 106, contact 118, wire 119, perforating magnet 15, wire 115, bus 116, wire 117, to other side of battery 95.

When polarized relay 12 is energized with positive direct current and alternating current relay 13 is deenergized, neutral armatures 102 and 103 of relay 12 make contact with front contacts 104, 105 and polarized armatures 106 and 107 are in the right hand position. Armature 108 of relay 13 makes contact with back contact 120. This position of the several armatures establishes a circuit through perforating magnet 16 as follows:—from battery 95, wire 98, wire 110, armature 108, back contact 120, wire 121, armature 103, front contact 105, wire 122, polarized armature 107, contact 123, wires 124 and 125, bus 116, wire 117, to the other side of battery 95.

When polarized relay 12 is energized with negative direct current and alternating current relay 13 is de-energized, neutral armatures 102 and 103 of relay 12 make contact with front contacts 104 and 105 and polar-

ized armatures 106 and 107 are in the left hand position. Armature 108 of relay 13 makes contact with back contact 120. This position of the several armatures establishes a circuit through perforating magnet 17 as follows:—battery 95, wires 98 and 110, armature 108, back contact 120, wire 121, armature 103, front contact 105, wire 122, armature 107, contact 126, wire 127, perforating magnet 17, wire 125, bus 116, wire 117, to the other side of battery 95.

When polarized relay 12 is deenergized and alternating current relay 13 is energized with alternating current, neutral armatures 102 and 103 of relay 12 make contact with back contacts 128 and 129 and armature 108 of relay 13 makes contact with front contact 109. This position of the several armatures establishes a circuit through perforating magnet 18 as follows:—from battery 95, wire 98, wire 110, armature 108, front contact 109, wire 111, armature 102, back contact 128, wire 130, perforating magnet 18, wire 131, bus 116, wire 117, to the other side of battery 95.

When polarized relay 12 is deenergized and alternating current relay 13 is also de-energized, neutral armatures 102 and 103 of relay 12 make contact with back contacts 128 and 129 and armature 108 of relay 13 makes contact with back contact 120. This position of the several armatures establishes a circuit through perforating magnet 19 as follows:—from battery 95, wires 98 and 110, armature 108, back contact 120, wire 121, armature 103, back contact 129, wire 132, perforating magnet 19, wire 133, bus 134, metallic contact 135, wires 136 and 117 to the other side of battery 95.

It will be noted that the circuit through perforating magnet 19 is taken through a circuit breaking device 135, so that this circuit is periodically made and broken. This circuit breaking device operates as follows:—Metallic contact plate 135, is attached to armature 88 and insulated therefrom. Every time the magnet 89 is energized, which is heretofore stated is say every 5-seconds, the contact through wires 134 and 136 is closed through the metallic plate 135. When magnet 89 is deenergized armature 88 is pulled to the right by spring 91 and the circuit between wires 134 and 136 is broken. By reason of this periodic breaking of the circuit through perforating magnet 19, a continuous perforation is made on the record sheet as long as relays 12 and 13 remain deenergized. This of course occurs every time a train enters a block when armature 6 of track relay 5 drops, thus breaking front contacts 7, 8 and 9 under which conditions, the main circuits from the dispatcher's office are broken. It will thus be seen that when a train enters a block, perforating magnet 19 commences to perforate, thus recording the exact time when

the train enters the block and this perforating magnet continues to perforate until the train has left the block, thus recording the length of time it remained in the block.

5 The circuit through perforating magnet 19 is the only one taken through the circuit breaker 135 and therefore this magnet is the only one that makes a continuous record. The circuits through perforating magnets 10 14, 15, 16, 17 and 18 are not taken through this circuit breaker and therefore when the circuit is closed through these several perforating magnets, only a single perforation is made on the record sheet. The perforating magnets are preferably so constructed 15 that when the magnet is energized, the perforating needle is driven through the record sheet by momentum but the perforating needle will immediately withdraw from the record sheet even if the armature of the perforating magnet is not released immediately. A perforating magnet of this character is 20 shown in my prior Patent, No. 1,138,804 granted to me, May the 11th, 1915. It is obvious that any one of the perforating magnets can be so arranged that a continuous record can be made by it as long as the circuit 25 through it is closed by connecting the same to bus 134, instead of bus 116. By such a connection, the circuit through the perforating magnet is periodically broken at circuit breaker 135.

Under certain conditions it may be 30 desirable to duplicate the six signals or instrumentalities along the track on the locomotive so as to forcibly bring these to the notice of the engineer, or the effects so obtained on the locomotive may also be used for the purposes of automatic train control or speed control. The means for duplicating 35 the signals on the locomotive or car will now be described.

In Fig. 1 train control rails 32 and 33 are 40 located adjacent to the track, train control rail 32 being a home train control rail, positioned near the beginning of the new block, and train control rail 33 being the distant train control rail, positioned approximately 45 braking distance from the beginning of the block. As hereinbefore described these train control rails, when track relay 5 is energized, are electrically connected to the dispatcher's office through line wire 35, armature 6 of track relay 5, front contact 9 and wire 50 31, and therefore the train control rails can be electrically conditioned to the six conditions hereinbefore described. If we now insert a cab circuit which is located on the locomotive between train control rails 32 or 33 55 and track rail 1 and place on the locomotive, a polarized relay similar to relay 10 and an alternating current relay similar to relay 11, the six signal indications may be duplicated on the locomotive.

60 The apparatus and circuits necessary to

duplicate the six signals on the locomotive are shown in Fig. 2, and are similar to the apparatus and circuits shown in my prior Patent No. 1,399,027 granted to me, December the 6th, 1921.

70 In Fig. 2 the six instrumentalities corresponding to the six electrical conditions of the train control rails are designated as signals A, B, C, D, E, F. While these instrumentalities in Fig. 2 are shown as lamps they may equally as well represent an electromagnetic device to which motion is given depending upon whether the circuit is energized or deenergized and such electromagnetic devices may be used for other purposes 75 or in addition to the display of signals to the engineer such as the proper control of speed control devices or electro-pneumatic air valves or both.

80 In Fig. 2 is shown an electrical contact shoe 137 so positioned on the locomotive as to make contact with train control rail 32. The contact shoe is hinged at 138. Train control rails 32 and 33 are inclined at the ends so as to form a ramp in the usual manner, such as 85 is shown in my prior Patent No. 1,140,623 granted May 25, 1915, and when the contact shoe slides along this ramp, the shoe is tilted, so as to break contacts 139, 140, and 141. This tilting motion of the shoe compresses 90 a spring 142. When the contact shoe leaves the other end of train control rail, spring 142 forces the contact shoe to the normal position, again closing contacts 139, 140 and 141. A metallic plate 143 fixed to contact 95 shoe 137 but insulated therefrom is so positioned as to make contact with contacts 140 and 141.

100 The locomotive also carries an alternating current relay 144 with its companion direct current winding 145, a polarized relay 146, a battery 147, and another battery 148. Alternating current relay 144 and its companion direct current coil 145 control the 105 position of armatures 149 and 150. Polarized relay 146 controls the position of neutral armatures 151, 152, and 153 and also polarized armatures 154, 155, 156 and 157. Polarized armatures 156 and 157 are pole changing 110 members of a switch for the purpose of changing the polarity of the flow of current from battery 147. Impedance coil 158 is inserted to prevent the flow of alternating current in the circuit, in which it is inserted, and condenser 159 is inserted to prevent the 115 flow of direct current in the circuit in which it is inserted.

120 The circuit for the direct current energy from the dispatcher's office between train control rails 32 or 33 to track rail 1 hereinbefore mentioned is as follows:—from train control rail 32, shoe 137, wire 160, wire 161, impedance coil 158, wire 162, polarized relay 146, wires 163, 164, 165 and 166, axle 167, wheel 168, to track rail 1 and thence the cir- 125 130

cuit is completed through the dispatcher's office as hereinbefore described.

The circuit for the alternating current energy from the dispatcher's office between train control rails 32 or 33 and track rail 1 heretofore mentioned is as follows:—from train control rail 32, contact shoe 137, wires 160 and 169, condenser 159, alternating current relay 144, wires 170, 164, 165 and 166, axle 167, wheel 168, to track rail 1 and thence the circuit is completed through the dispatcher's office as heretofore described. Armature 149 of relay 144 controls a stick circuit through coil 145, which will be described later and armature 151, of relay 146 controls a similar stick circuit for relay 146, which will also be described later.

It will thus be seen that when contact shoe 137 on the locomotive is in contact with a train control rail 32 or 33, polarized relay 146 and alternating current relay 144 are under the control of the dispatcher by means of manually operated switches 37 and 38 and by the several positions of these switches six different combinations of circuits can be established by relay 146 and 144 similar to the six circuits controlled by relays 10 and 11 along the track.

I will now describe the six electrical conditions of relays 146 and 144 and the corresponding circuits established through signals A, B, C, D, E and F, when contact shoe 137 is in contact with a train control rail.

First:—When polarized relay 146 is energized with positive direct current and alternating current relay 144 is energized with alternating current, neutral armatures 151, 152 and 153 of relay 146 make contact with front contacts 171, 172 and 173 and polarized armatures 154, 155, 156 and 157 of relay 146 are in the right hand position, thus making contact with their respective contacts 174, 175, 176 and 177. Armatures 149 and 150 of relay 144 make contact with front contacts 178 and 179. This position of the several armatures establishes a circuit through signal A as follows:—from one side of battery 147, wires 180 and 181, contact 176, polarized armature 156, wire 182, armature 150, front contact 179, wire 183, armature 152, front contact 172, wire 184, polarized armature 154, contact 174, signal A, wires 185, 165 and 186, polarized armature 157, contact 177, wire 187, to the other side of battery 147.

As the contact shoe 137 leaves the other end of the train control rail, the position of the armatures of relays 146 and 144 are maintained in the same position after the electro-motive forces from the dispatcher's office cease to influence them through the following two stick circuits:—As contact shoe 137 leaves the train control rail, spring 142, closes contact 139, 140 and 141 and a stick circuit is established through coil 145 of relay 144 as follows:—from battery 148, wire 188, coil 145,

wire 189, contact 141, metallic plate 143, contact 140, wire 190, front contact 178, armature 149, wire 191, to other side of battery 148.

The second stick circuit is established through relay 146 as follows:—from battery 147, wires 180 and 181, contact 176, polarized armature 156, wire 192, armature 151, front contact 171, wire 193, contact 139, contact shoe 137, wires 160 and 161, impedance coil 158, wire 162, polarized relay 146, wires 163, 164 and 186, polarized armature 157, contact 177, wire 187 to the other side of battery 147.

Second:—When polarized relay 146 is energized with negative direct current and alternating current relay 144 is energized with alternating current, neutral armatures 151, 152 and 153 of relay 146 make contact with front contacts 171, 172 and 173 but polarized armatures 154, 155, 156 and 157 of relay 146 are now in the left hand position thus making contact with their respective contacts 194, 195, 196 and 197. Armatures 149 and 150 of relay 144 make contact with front contacts 178 and 179. This position of the several armatures establishes a circuit through signal B as follows:—from one side of battery 147, wire 187, contact 196, polarized armature 156, wire 182, armature 150, front contact 179, wire 183, armature 152, front contact 172, wire 184, armature 154, contact 194, signal B, wires 185, 165 and 186, armature 157, contact 197, wire 180, to the other side of battery 147, the circuit being traced against the flow of current.

As the contact shoe 137 leaves the other end of the train control rail, the position of the armatures of relays 146 and 144 are maintained in the same positions through the two stick circuits. The stick circuit through relay 144 being the same as hereinbefore described and the stick circuit through 146 being as follows:—battery 147, wire 180, contact 197, armature 157, wire 186, wire 164, wire 163, polarized relay 146, wire 162, impedance coil 158, wires 161 and 160, contact shoe 137, contact 139, wire 193, front contact 171, armature 151, wire 192, armature 156, contact 196 and wire 187, to the other side of battery 147.

Third:—When polarized relay 146 is energized with positive direct current and alternating current relay 144 is deenergized neutral armatures 151, 152 and 153, of relay 146 make contact with front contacts 171, 172 and 173 and polarized armatures 154, 155, 156 and 157 of relay 146 are in the right hand position thus making contact with their respective contacts 174, 175, 176 and 177. Armatures 149 and 150 of relay 144 have now dropped away from their front contacts and armature 150 now makes contact with back contact 198. This position of the several armatures establishes a circuit through signal C as follows:—from battery 147, wires 180 and 181, contact 176, armature 156, wire 182, armature 150, back contact 198, wire 199, 130

armature 153, front contact 173, wire 200, armature 155, contact 175, signal C, wires 185, 165 and 186, armature 157, contact 177, and wire 187 to the other side of battery 147.

As the contact shoe 137 leaves the other end of the train control rail, armatures 149 and 150 of relay 144 remain in the deenergized position, since the stick circuit controlling coil 145, while contacts 140 and 141 are now closed, is now open at front contact 178. The stick circuit of relay 146 however, is still operative as heretofore described and the position of the armatures of this relay remain the same.

Fourth:—When polarized relay 146 is energized with negative direct current and alternating current relay 144 is deenergized neutral armatures 151, 152, and 153 of relay 146 make contact with front contacts 171, 172 and 173 but polarized armature 154, 155, 156 and 157 of relay 146 are now in the left hand position thus making contact with their respective contacts 194, 195, 196 and 197. Armatures 149 and 150 of relay 144 have now dropped away from their front contacts and armature 150 now makes contact with back contact 198, this position of the several armatures establishes a circuit through signal D as follows:—from battery 147, wire 187, contact 196, armature 156, wire 182, armature 150, back contact 198, wire 199, armature 153, front contact 173, wire 200, armature 155, contact 195, signal D, wires 185, 165 and 186, armature 157, contact 197, wire 180, to the other side of battery 147, circuit being traced against the flow of current.

As the contact shoe 137 leaves the other end of train control rail, the stick circuit through relay 144 remains inoperative as hereinbefore described while the stick circuit through relay 146 remains operative as previously described.

Fifth:—When polarized relay 146 is deenergized and alternating current relay 144 is energized with alternating current, neutral armatures 151, 152 and 153, drop away and armatures 152 and 153 make contact with the back contacts 201 and 202. Armatures 149 and 150 of relay 144 make contact with front contacts 178 and 179. This position of the several armatures establishes a circuit through signal E as follows:—from battery 147, wires 180 and 181, contact 176, armature 156, wire 182, armature 150, front contact 179, wire 183, armature 152, back contact 201, wire 203, signal E, wires 185, 165 and 186, polarized armature 157, contact 177, and wire 187, to the other side of battery 147.

As the contact shoe 137 leaves the other end of the train control rail, the stick circuit through relay 144 is operative since the front contact 178 is now closed but the stick circuit through relay 146 is inoperative since the front contact 171 is now open.

Sixth:—When polarized relay 146 and al-

ternating current relay 144 are both deenergized, neutral armatures 151, 152 and 153 of relay 146 drop away and armatures 152 and 153 make contact with back contacts 201 and 202, armatures 149 and 150 of relay 144 also drop away and armature 150 makes contact with back contact 198. This position of the several armatures establishes a circuit through signal F as follows:—from battery 147, wires 180 and 181, contact 176, armature 156, wire 182, armature 150, back contact 198, wire 199, armature 153, back contact 202, wire 204, signal F, wires 185, 165 and 186, armature 157, contact 177, wire 187, to the other side of battery 147. It is to be observed that the polarized armatures 154, 155, 156 and 157 remain in their position upon a deenergization of 70 146, so that a circuit can always be made through them. Of course applicant does not intend to exclude any other type of 75 relay which may be applicable for this situation, as the well known polarized rotary relay is not to be excluded, as this relay may be used to close a circuit when deenergized or when negatively or positively energized. 80

As the contact shoe 137 leaves the other end of train control rail, both stick circuits are now inoperative since front contacts 178 and 171 are now open and therefore the existing position of the several armatures is continued until an energized train control rail is reached. 85

It must be understood that each time contact shoe 137 slides on to a train control rail, both stick circuits, one through relay 144 120 and the other one through relay 146, are opened at contacts 139, 140 and 141 and therefore both relays 146 and 144 would become deenergized, resulting in the display of signal F, unless energy of some character is 125 furnished from the dispatcher's office, while contact shoe 137 is in contact with a train control rail.

It will thus be seen that under any of the six electrical conditions of the train control rails, one of the six signals on the locomotive is established, when a locomotive passes a train control rail and the particular signal established at the train control rail is continued on the locomotive until the next train control rail is encountered. 115

While the dispatcher is thus able by placing switches 37 and 38 in the several positions described, to display six different signals on the locomotive, any one of these signals is annulled and made inactive except signal F, if there is a train in the block ahead, for the reason that the circuit establishing different electrical conditions in train control rails passes through armature 6 of track relay 5, and when there is a train in the block ahead, the circuit from the dispatcher's office is broken at front contact 9 of armature 6. When this condition exists no electrical energy can reach train control rails 32 or 33, 120

therefore invariably signal F will be displayed on the locomotive, irrespective of whether switches 37 and 38 in the dispatcher's office are positioned to charge the train control rails with electrical energy.

The purpose of the invention is first of all to provide instrumentalities or signals to make the operation of trains safe, but in addition to provide instrumentalities or signals which will enable the dispatcher to facilitate the movement of trains. For instance, signals A, B, and F may be used for safety purposes, signal A indicating a clear track ahead, signal B indicating caution and signal F indicating stop. The other three signals may be used for facility purposes, such as indicating to the engineer to stop at the next siding or remain on the main track or to stop at the next siding and pull into the siding or to stop at the next station and report to the dispatcher. Or any of the six signals may be used for any purpose designated by the executive officers of the railway.

Although I have particularly described and illustrated one preferred physical embodiment of my invention and explained the principle and construction thereof, nevertheless I desire to have it understood that the form selected is merely illustrative, but does not exhaust the possible physical embodiment of means underlying my invention.

What I claim as new and desire to secure by Letters Patent of the United States is:

1. In a railway train control system, in combination: a trackway; means dividing the trackway into electrically isolated sections; a vehicle movable upon the trackway; train control instrumentalities positioned adjacent each of the sections; train control instrumentalities positioned upon the vehicle; a central station; means manually controlled positioned at the central station whereby the train control instrumentalities adjacent each section are conditioned to one of six different conditions, and the train control instrumentalities upon the vehicle are correspondingly conditioned by cooperation with said first train control instrumentalities, including means for recording at the central station the particular condition effected.

2. In a railway train control system, in combination: a trackway; a vehicle movable upon the trackway; means dividing the trackway into electrically isolated sections; a central station; means located at the central station and means located along the trackway and means located on the vehicle whereby manual operation to any one of six different signal conditions may be established along the trackway and on the vehicle, and record thereof made at the central station by cooperation between said means.

3. In a railway train control system, in combination; a trackway; means dividing the trackway into a plurality of isolated track

circuit sections; a ramp associated with each track circuit section; means for causing the ramp to have six electrical conditions; a vehicle having means for selectively receiving thereon an indication of any one of the six electrical conditions of the ramp and means co-operative with the ramp for transmitting said conditions; and means positioned at a central station for recording the electrical condition influencing the vehicle.

4. In a railway train control system, in combination; a trackway; means dividing the trackway into a plurality of isolated track circuit sections; a vehicle movable on the trackway; train control instrumentalities positioned adjacent each section; train control instrumentalities positioned upon the vehicle; a central station; and means manually controlled positioned at the central station whereby the train control instrumentalities adjacent each section are conditioned to one of six different conditions and the train control instrumentalities upon the vehicle are correspondingly conditioned by cooperation therewith.

5. In a railway train control system, in combination; a trackway; means dividing the trackway into electrically isolated sections; train control instrumentalities positioned adjacent each of the said sections; a central station; means manually controlled positioned at the central station whereby the train control instrumentalities adjacent each section are conditioned to one of six different conditions; and means controlled by the presence of a train in a preceding section for automatically establishing a particular condition of the train control instrumentalities at the entrance to such section irrespective of the operation of said manually controlled means.

6. In a railway train control system in combination; a trackway; means dividing the trackway into a plurality of isolated track sections; a vehicle movable upon the trackway; train control instrumentalities positioned adjacent to each of the said sections; a central station; means manually controlled positioned at the central station whereby the train control instrumentalities adjacent each section are conditioned to one of six different conditions, means for automatically producing one of said conditions when a vehicle is in a preceding section and means for making a record at the central station of the particular condition established.

7. In a railway signal and dispatching system; a trackway divided into blocks; more than three different signals for directing the movement of a train approaching each block in a single direction; and two means for the control of the signals, one means being a track circuit and the other being located at a central point.

8. In a railway signal and dispatching system; a train; more than three signals for governing the movement of a train in a single direction; two means for the control of the signals, one being automatic, the other manual; and a central office containing instrumentalities for actuating the manual control means. 70
9. In a railway signal and dispatching system; a train; more than three instrumentalities for governing the movement of a train in a single direction; two means for the control of the governing means, one being automatic, the other manual; and a central office containing instrumentalities for actuating the manual control means. 75
10. In a railway signal and dispatching system; a train; a central office; more than three signals for governing the movement of a train in a single direction; and two means for the control of the signals, one being automatic and the other a circuit controller located at the central office and manually operated. 80
15. In a railway signal and dispatching system; a trackway divided into blocks, each block provided with a track circuit; a central office; sources of electric currents of different kinds at the central office; more than three signals governing train movements into each block; a circuit between said central office and said signals for conveying said electric currents to said signals; means at the central office for conditioning said circuit in more than three different ways, one way for each signal from said sources of current, and track circuit means for also conditioning said signals. 85
20. In a railway signal and dispatching system; a trackway divided into blocks, each block provided with a track circuit; a central office; sources of electric currents of different kinds at the central office; more than three signals governing train movements into each block; a circuit between said central office and said signals for conveying said electric currents to said signals; means at the central office for conditioning said circuit in more than three different ways, one way for each signal from said sources of current, track circuit means for also conditioning said signals; and means for indicating at the central office the location of a train, said means being actuated by said currents. 90
25. In a railway signal and dispatching system; a trackway divided into blocks; a track circuit for each block; more than three signals for governing trains entering a block in a single direction, one of said signals indicating proceed to a train, another signal indicating stop; means at a central office for displaying any one of more than three signals; and track circuit means for preventing the display of a proceed signal when a train is in the block. 95
30. In a railway signal and dispatching system; a trackway divided into blocks, each block provided with a track circuit; more than three signals governing train movements in a single direction into each block; a circuit for each signal; means at a central office for conditioning each signal circuit; and means independent of said central office means for also conditioning said signal circuits. 100
35. In a railway signal and dispatching system; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; means controlled by said central station means for automatically indicating the signal displayed at the entrance of a block and other automatically operative indicating means for indicating the movement of a vehicle through said block. 105
40. In a railway signal and dispatching system; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; means controlled by said central station means for automatically indicating the signal displayed at the entrance of a block and other automatically operative indicating means for indicating the movement of a vehicle through said block. 110
45. In a railway signal and dispatching system; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; means controlled by said central station means for automatically indicating the signal displayed at the entrance of a block and other automatically operative indicating means for indicating the movement of a vehicle through said block. 115
50. In a railway signal and dispatching system; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; means controlled by said central station means for automatically indicating the signal displayed at the entrance of a block and other automatically operative indicating means for indicating the movement of a vehicle through said block. 120
55. In a railway signal and dispatching system; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; means controlled by said central station means for automatically indicating the signal displayed at the entrance of such block; and other automatically oper- 125
60. In a railway signal and dispatching system; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; means controlled by said central station means for automatically indicating the signal displayed at the entrance of such block; and other automatically oper- 130
65. In a railway signal and dispatching system; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; means controlled by said central station means for automatically indicating the signal displayed at the entrance of such block; and other automatically oper- 135

ative indicating means for indicating the movement of a vehicle through said block.

19. In a railway train control system, in combination; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; means controlled by said central station means for automatically recording the signal displayed at the entrance of a block and other automatically operative recording means for recording the movement of a vehicle through said block.

20. In a railway train control system, in combination; a trackway divided into blocks; more than three signals each differentiated from the other, located adjacent each block; vehicle carried train control instrumentalities corresponding to said signals; control rails adjacent each block to the electrical condition of which said control instrumentalities are severally responsive; central station means for selectively operating a particular signal and establishing an electrical condition of said control rails corresponding to the signal selected; means controlled by said central station means for automatically giving a continuous record of the signal displayed at the entrance of such block; and other automatically operative recording means for recording the movement of a vehicle through said block.

21. In a railway train control system, in combination; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; and central station means for selectively operating a particular signal and establishing an electrical condition of said control means corresponding to the signal selected.

22. In a railway train control system, in combination; a trackway divided into blocks; more than three signals, each differentiated from the other, located adjacent each block; vehicle carried train control instrumentalities corresponding to said signals; control means adjacent each block to the electrical condition of which said control instrumentalities are severally responsive; central station means for selectively operating a particular signal and establishing an electrical condition of said control means corresponding to the signal selected; and means controlled by the

presence of a vehicle in a block for automatically selecting the operation of a particular signal at the entrance to such block regardless of the selection for which said central station means may have been operated.

23. In a railway signal and dispatching system; a train; a trackway divided into blocks; a track circuit for each block; more than three fixed signals at the entrance to each block; a cab signal on each train; a circuit controlled at a central office and controlling said signals; and track circuit means for also controlling said signals.

24. In a railway signal and dispatching system; a train; a trackway divided into blocks; a track circuit for each block; more than three fixed signals at the entrance to each block; more than three cab signals on each train; a circuit controlled at a central office and controlling said signals; track circuit means for also controlling said signals; and means at a central office for indicating and recording the progress of the train from block to block, said means being conditioned selectively by said control circuit.

25. In a railway signal and dispatching system; a train; a trackway divided into blocks; a track circuit for each block; more than three cab signals on each train; a circuit controlled at a central office and controlling said signals; and track circuit means for also controlling said signals.

26. In a railway signal and dispatching system; a train; a trackway divided into blocks; a track circuit for each block; more than three cab signals on each train; a circuit controlled at a central office and controlling said signals; track circuit means for also controlling said signals; and means at a central office for indicating the progress of the train from block to block, said means being conditioned selectively by said control circuit.

27. In a railway train control system, in combination; a trackway divided into blocks; more than three signals, each differentiated from the other, located adjacent each block; circuits for said signals; a relay capable in accordance with its electrical condition, of selectively conditioning the circuit of a particular signal; central station means for varying the condition of said relay, said central station means including circuits having a common wire; a track battery and track relay for each block; and an armature controlled by the track relay and operative to open or close the circuits of said central station means at a point in said common wire.

28. In a railway signal and dispatching system; a trackway divided into blocks; a track circuit for each block; more than three fixed signals at the entrance to each block for giving three different indications to a train proceeding in a given direction; a circuit controlled at a central office and control-

ling said signals; and track circuit means for also controlling said signals.

29. In a railway signal and dispatching system; a trackway divided into blocks; a track circuit for each block; more than three fixed signals at the entrance to each block for giving three different indications to the train; a circuit controlled at a central office and controlling said signals; track circuit means for also controlling said signals; and means at a central office for indicating the movement of trains, said means being conditioned selectively by said control circuit.

30. In a railway signal and dispatching system; a trackway divided into blocks, each block provided with a track circuit; a central office; currents of different kinds at the central office; more than three signals governing train movements into each block; an electrical device along the track; a circuit between said central office and said electrical device; means at the central office for conditioning said electrical device in more than three different ways, one for each signal; and track circuit means for also conditioning said signals.

PAUL J. SIMMEN.
